(57) **CLAIM**

We claim the ornamental design for a thermostat, as shown and described.

DESCRIPTION

FIG. 1 is a front perspective view from above of a thermostat according to the claimed design;

FIG. 2 is a front perspective view from below of the claimed design of FIG. 1;

FIG. 3 is a front side view of the claimed design of FIG. 1;

FIG. 4 is a rear side view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and,

FIG. 8 is a bottom view of the claimed design of FIG. 1.

Any portion of the thermostat depicted in broken lines in the drawings forms no part of the claimed design. Broken lines formed by equal length dashes show unclaimed portions of the design. Broken lines formed of unequal length dashes (i.e., dash-dot) show boundaries between claimed and unclaimed portions of the design.
